(57) **CLAIM**

The ornamental design for a flash hider flashlight head module, as shown and described.

DESCRIPTION

FIG. 1 is a perspective view of the flash hider flashlight head module in accordance with the present invention;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The elements depicted in broken line in the various figures are included for environmental purposes only, and form no part of the claimed design.
